UNITED STATES PATENT OFFICE.

JESSE NEWBAUER, OF SAN FRANCISCO, CALIFORNIA.

WAIST-LINING.

SPECIFICATION forming part of Letters Patent No. 680,675, dated August 13, 1901.

Application filed June 5, 1900. Serial No. 19,177. (No model.)

To all whom it may concern:

Be it known that I, JESSE NEWBAUER, a citizen of the United States, and a resident of the city and county of San Francisco, in the 5 State of California, have invented a new and useful Improvement in Close-Fitting Waist-Linings for Ladies' Wear, of which the following is a specification.

This invention relates to an improved close-fitting waist-lining for wrappers, shirt-waists, and other similar garments for ladies' wear; and the invention has for its object to provide a waist-lining that will adjust itself or accommodate itself without alteration to different 15 measurements of bust and waist, whereby the same garment will fit several different persons who may vary in dimensions of bust or waist, or both, and where the other measurements of the garment—such as the neck, the 20 sleeves, and the length of waist or skirt—are suitable.

To this end my said improvement consists in a waist-lining of the close-fitting kind formed of inelastic material and having inserted bust and waist sections of elastic material in the front, said elastic sections extending from the waist-line to points above the bust and opposite the armpits, but no higher, as hereinafter described, and pointed 30 out in the claim at the end of this specification.

The following description explains at length the manner in which I construct, apply, and produce this improved waist-lining, 35 reference being had to the accompanying drawings, forming part thereof.

Figure 1 of the drawings represents, in front view, a close-fitting waist-lining for a lady's wrapper formed in accordance with my invention, the garment proper covering the waist-lining being indicated by dotted lines. Fig. 2 is a back view of the waist-lining.

The front sections *a*, the back *b*, and the sides *c* of the waist-lining are formed of ordinary lining material, such as cotton fabric, which is practically inelastic, and the parts are cut to size according to the pattern used

and meet over the shoulders and beneath the armpits.

In each front section *a* of the body is inserted in an opening cut away on corresponding outlines a pear-shaped section *d* of elastic material, with the large end of curvilinear outline at the top and with the contracted portion extending downward therefrom to 55 the waist-line.

The elastic section *d* is united to the inelastic material composing the front *a* by a lap-seam and rows of stitching along the edges, and the top, being approximately circular in 60 outline or corresponding to the segment of a circle, is so placed that the chord or the greatest horizontal diameter thereof is situated on a transverse line extending across the front from one armpit to the other and on a median 65 line running through the center of the bust or substantially on such line. The specific location of the widest portion of the elastic section *d* at this point prevents the lining from cutting the wearer under the arms and 70 causes it to accommodate itself to abnormally large busts. From this top portion the contracted portion of the elastic section extends downwardly in gradually-converging lines to the bottom of the waist. In this form the 75 curvilinear or rounded outline of the section *d*, surrounding or taking in the projecting breast portion, will by virtue of its elastic quality stretch to a greater or less degree, corresponding to the size of the bust, while 80 the contracted portion *d* below, yielding in like manner, will allow the lining to expand on the waist-line.

Knit or woven ribbed fabric is a good material to use for the sections *d*, as the same 85 has the advantage of being washable and will ordinarily be found to possess the desired elastic quality and to retain it to a degree sufficient to draw and retain the waist to a proper fit.

Having thus fully described my invention, what I claim as new therein, and desire to secure by Letters Patent, is—

A waist-lining for ladies' wear consisting of

the back, sides, and front sections of inelastic material meeting over the shoulders and under the armpits; and the inserted sections of elastic material in the front, said elastic 5 sections having enlarged upper portions of curvilinear outline circumscribing the breasts with their greatest horizontal diameters opposite the armpits, and contracted lower por-

tions continuing downwardly from the breast to the bottom of the waist.

In testimony that I claim the foregoing I have hereunto set my hand and seal.

JESSE NEWBAUER. [L. S.]
